UNITED STATES PATENT OFFICE.

CHARLES H. TOMLINSON, OF MANSFIELD, OHIO, ASSIGNOR TO THE TOMLINSON COUPLER COMPANY, OF DENVER, COLORADO, A CORPORATION OF SOUTH DAKOTA.

DRAW-BAR CARRIER.

934,375.

Specification of Letters Patent. Patented Sept. 14, 1909.

Application filed January 26, 1907. Serial No. 354,352

To all whom it may concern:

Be it known that I, CHARLES H. TOMLINSON, a citizen of the United States, residing at Mansfield, in the county of Richland and State of Ohio, have invented certain new and useful Improvements in Draw-Bar Carriers, of which the following is a specification.

My invention relates to a movable hanger or draw-bar carrier and is primarily adapted to be used for yieldingly suspending draw-bars and couplers having a radial and horizontal movement and consists, primarily, in a carrier which is adapted to be used to support them and comprises supporting means suspended from a movable frame to support a draw-bar.

One of the objects of my invention is to provide a draw-bar carrier that will permit the draw-bar and coupling of each car when coupled to remain constantly on a plane with each other and in proper position notwithstanding the fact that one of the cars is not on the same grade or plane as the other.

A further object of my device is to provide means whereby the supporting means upon which the draw-bar rests will automatically adjust itself so as to keep the draw-bars and couplings on a plane with each other on any plane or grade necessary to run the cars on.

Further objects of my device are to provide means of permitting the usual lateral movement of the draw-bar in conjunction with a vertical movement, and to provide a support for the draw-bar and coupling that will yieldingly suspend their weight under normal conditions by securing the supporting means to the car body under such a tension that it will balance their combined weight and when any undue strain or pressure is brought to bear upon the sleeve the movable hangers carrying the supporting means will move downward or upward according to the strain or pressure they are subjected to on account of any difference of grade caused by the tilting of the car or otherwise. I attain these and other objects by the mechanism illustrated in the accompanying drawings in which—

Figure 1 is a side elevation of my device. Fig. 2, is a front elevation of the carrier with one side in vertical section taken through the line m, m , of Fig. 1. Fig. 3, is a horizontal section of the carrier taken through the line n, n , of Fig. 1. Fig. 4 is a plan view of the draw-bar carrier and the supporting

means shown in Figs. 1, 2, and 3 in their relative positions attached to a car the outline of which is shown by the dotted line. This view also shows the radial movement of the couplers. Fig. 5, shows a section of track with one end inclined downward illustrating a grade with sections of two cars coupled upon the grade showing the draw-bars and couplers supported by the carrier on a plane with each other and the supporting springs of the yoke mechanism of the car on the grade compressed by the draw-bar which exerts more than a normal pressure or strain against the yielding supporting means when both cars are not on a plane with each other. Fig. 6 is a side elevation of my device with one car inclined upward illustrating the grade with sections of two cars coupled upon the grade showing the draw-bars and couplers on an incline and in alignment with each other. It also shows the draw-bar pivotally connected for lateral movement and also for vertical movement above and below its normal position.

In the construction of my device, I prefer to use a frame comprising a base 1 with two downwardly depending arms 2 and 3 spaced apart leaving an opening 4. Vertical flanges 5 and 6 are made integral with the arms spaced apart and project downwardly therefrom intersecting with the horizontal upper and lower flanges 7 and 8 respectively, which project from said arms and in conjunction therewith form rectangular recesses or casings to inclose and support the compression springs 9, the purpose of which will be described hereinafter. Hangers 10 are provided for each casing with the upper extremities 11 turned at an angle with the body portion and adapted to align with suitable apertures formed in the horizontal flanges 7. The lower extremities 12 of the hangers have eyes formed thereon with apertures formed therein at right angles to the apertures formed in the lower extremities. An opening 13 is provided in the lower extremities and side walls of the arms 2 and 3 to permit the lower extremity of the hangers to be inserted therein leaving the enlarged lower portion 14 of the hangers extending inwardly flush with inner faces of the arms 2 and 3 retaining them in place and preventing the draw-bars from catching under the inner walls of the arms upon their return to their normal position when relieved.

of undue strain or pressure caused by the cars being on a grade or different plane when coupled. A sleeve 15 is interposed between the inner faces of the enlarged lower portions of the hangers and mounted on the pin 16 which is held in place by the cotter pins 17 and 18. The hangers 10 and sleeve 15 when connected together form substantially an inverted yoke which is adapted to move vertically as will be described.

The coil springs 9 are inserted in the casings formed by the flanges as hereinbefore described with their lower ends resting on the horizontal flanges 8 and the upper ends 15 contacting with the under portion of the angular ends 11 of the hangers 10 thereby yieldingly suspending the parts comprising the inverted yoke. Through-going bolts 19 pass downwardly through the flange 7, angular ends 11 of the hangers through the inner periphery of the coil springs and thence through the flanges 8 leaving the ends projecting below and are retained in place by any well known fastening means. 20 The coil compression springs 9 are made of such a size or tension as will counter-balance the weight of the inverted yoke, the draw-bar and coupler that they yieldingly support whereby the draw-bars and coupling are retained on a plane for coupling purposes under normal conditions as when the cars are upon the same grade.

Referring to Figs. 1 and 2, the upper portion or base 1 of the frame is provided with a tee slot 21 which is adapted to engage with a curved tee bar 23 (see Fig. 4) which movably supports the frame and carrier and permits radial or lateral movement of the draw-bars 20. The draw-bars are pivoted 35 for lateral and vertical movement upon the pin 24, the opening being enlarged and rounded on the edges toward the center to permit of vertical movement above and below the normal position of the draw-bars. 40 See Fig. 6. This is an old and well-known method of connecting vertically movable draw-bars to the car, and forms no part of my present invention. The draw-bars 20 are pivoted upon the pin 24 in the usual 45 manner.

The draw-bars and coupling devices are secured to the draft rigging of the cars by any well known means and form no part of my invention.

55 The operation of my draw-bar carrier is as follows: Each draw-bar 20 is supported on the sleeve 16 between the faces of the enlarged portions 14 of the hangers 10 and the tension of the springs 9 is adjusted to 60 maintain the draw-bar and coupling at the same plane as the car body under normal conditions. When one (or both) of the cars are upon a different grade as shown in Fig. 5, a strain or pressure is brought to bear 65 upon the sleeve 16 forcing the sleeve and

hangers supporting it downward by the tilting of the car body (see Fig. 5) and compressing the spring 9 to such an extent as will keep the draw-bars and coupling on a plane with each other when coupled notwithstanding the fact that the cars are running upon different grades with respect to each other. When the sleeve and hangers forming the inverted yoke are relieved from the strain or pressure the sleeve automatically 75 returns to its normal position.

I do not confine myself to the exact construction shown, as it is obvious to any one skilled in the art that many changes can be made without departing from the principle 80 involved.

Having fully described my invention, what I claim and desire to secure by Letters Patent is:

1. A draw-bar carrier, comprising a yoke-shaped frame with rectangular recesses formed therein, means to secure said frame to a car, hangers mounted within the recesses of said frame, means to yieldingly suspend said hangers, and means interposed 90 between the lower extremities of the hangers to support a draw-bar.

2. In a draw-bar carrier, an arc shaped bar, a frame movably suspended from said bar to provide for lateral movement, hangers 95 fitted to said frame and adapted to move vertically, means to yieldingly support said hangers, said hangers and means being located on each side of the draw-bar, a sleeve interposed between the lower extremities of the hangers to support a draw-bar, substantially as and for the purpose described.

3. In a draw-bar carrier, a frame movably supported to provide for lateral movement, hangers mounted on said movable frame 105 having the upper ends thereof turned at right angles with the body portion and provided with suitable apertures, bolts secured to each side of the frame and adapted to pass through said apertures formed in the 110 hangers, springs mounted on the frame and surrounding said bolts, said springs exerting a pressure against the hangers to yieldingly support the hangers in normal position, a sleeve interposed between the free ends of the 115 hangers, a draw-bar pivoted for vertical and lateral movement and adapted to be supported upon said sleeve substantially as and for the purpose described.

4. The combination of a draw-bar carrier 120 pivotally secured to a car body, an arc shaped bar secured to the car, a frame secured to said pivoted bar for lateral movement, bolts secured to said frame, hangers loosely fitted to said bolts and mounted in 125 the arms of the frame for vertical movement, and yielding means to support said hangers in their normal position.

5. The combination of a draw-bar carrier comprising an arc shaped supporting bar 130

- secured to a car body, a frame provided with two depending arms movably secured to said bar, hangers mounted on said arms and adapted to move vertically thereon, yielding movement; said draw-bar being also pivotally secured to the car for vertical movement above and below its normal position.
- 5 9. The combination of a draw-bar carrier, and a bar, said draw-bar carrier comprising a frame on said bar, means yieldingly attached to said frame to allow of downward movement of said means and providing an opening between the top of a draw-bar resting thereon, and the under part of the frame to allow for upward movement of said draw-bar.
- 10 10. The combination of a draw-bar carrier consisting of a bar, a frame mounted on said bar for lateral movement, yielding means mounted on said frame for vertical movement with a draw-bar resting thereon which is adapted to move upward and downward from its normal position.
- 15 11. In a draw-bar carrier, the combination of a bar secured to the lower portion of a car, a frame with depending arms mounted on said bar for lateral movement, and yielding supporting means mounted on said arms for vertical movement of a draw-bar resting thereon.
- 20 12. In a draw-bar carrier, the combination of a bar secured to the lower portion of the car; of a yoke-shaped frame movably supported by said bar for lateral movement and a yoke-shaped yielding supporting means mounted on said frame for vertical movement with a draw-bar resting thereon adapted to move above and below its normal position.
- 25 13. The combination of a draw-bar carrier and a bar; said draw-bar carrier comprising a frame movably supported by said bar, a frame yieldingly supported by said movable frame with a draw-bar pivoted for vertical and lateral movement resting thereon; said draw-bar being adapted to move above or below its normal position when coupled to cars on different grades.
- 30 45. 8. In a draw-bar carrier, the combination of a bar secured to the lower portion of a car, a frame movably supported by said bar, a frame yieldingly supported upon said movable frame, a draw-bar resting thereon and pivotally secured to the car for lateral movement; said draw-bar being also pivotally secured to the car for vertical movement above and below its normal position.
- 35 40 45 50 55 60 65 70 75 80 85 90 95
7. In a draw-bar carrier comprising a frame formed substantially yoke shaped having casings formed on each side thereof, bolts secured within said casings, hangers having the upper portion bent at right angles with the body portion mounted on said bolts for vertical movement, yielding supporting means adapted to contact with the bent portion of the hangers and support said hangers in normal position, a sleeve interposed between the free ends of said hangers whereby the sleeve and hangers form an inverted yoke adapted to move vertically under pressure when supporting a draw-bar, substantially as and for the purpose described.
8. In a draw-bar carrier, the combination of a bar secured to the lower portion of a car, a frame movably supported by said bar, a frame yieldingly supported upon said movable frame, a draw-bar resting thereon and pivotally secured to the car for lateral movement; said draw-bar being also pivotally secured to the car for vertical movement above and below its normal position.

In testimony whereof I affix my signature in presence of two witnesses.

CHARLES H. TOMLINSON.
